UNITED STATES PATENT OFFICE.

GEORGE FINN, OF NEWARK, NEW JERSEY.

SAD-IRON.

SPECIFICATION forming part of Letters Patent No. 705,573, dated July 29, 1902.

Application filed December 4, 1901. Serial No. 84,602. (No model.)

To all whom it may concern:

Be it known that I, GEORGE FINN, a citizen of the United States, and a resident of Newark, in the county of Essex and State of New Jersey, have invented certain new and useful Improvements in Sad-Irons, of which the following is a specification.

The invention relates to improvements in sad-irons; and it consists in the novel features, 10 construction, and combinations of parts hereinafter described, and particularly pointed out in the claims.

The object of the invention is to provide a new and improved self - heating sad - iron 15 pointed at both ends and capable of convenient use.

A further object of the invention is to provide a self-heating sad-iron in which the maximum efficiency may be attained from the 20 combustible material therein.

A further object of the invention is to produce a self-heating sad-iron having a top 25 plate or cover capable of being very conveniently applied to and removed from the body of the iron and of being secured in place by means which are effective, simple, and capable of convenient use.

The invention will be fully understood from the detailed description hereinafter presented, 30 reference being had to the accompanying drawings, in which—

Figure 1 is a top view of a sad-iron constructed in accordance with and embodying the invention. Fig. 2 is a vertical section of 35 same on the dotted line 2 2 of Fig. 1, and Fig. 3 is a vertical transverse section of same on the dotted line 3 3 of Fig. 2.

In the drawings, 10 designates the body of the sad-iron, 11 the top plate thereof, and 12 40 the handle, secured to said top plate 11.

The body 10 of the sad-iron is hollow to receive the combustible material and is elliptical in horizontal section, being pointed at both ends, as illustrated, whereby either end 45 may be used as the forward end of the iron in ironing, said ends corresponding exactly with one another. In the opposite sides of the body 10 are draft-apertures 13, which open into the interior of the body 10 below 50 the downwardly and inwardly converging flanges 14, constituting a part of the said

body 10 and which are elongated, as shown in Fig. 2, and correspond with one another. The draft-apertures 13 are preferably elongated, as defined in Fig. 2, and upon the opposite sides of the body 10 are provided the pivoted gates 34, adapted when in their lower position to close the draft-apertures 13. The gates 34 close the apertures 13 when turned downward in the position in which they are 60 illustrated in Fig. 3, and the said gates 34 may be turned upward, when desired, so as to fully or more or less expose the apertures 13 for the passage of the air therethrough. The flanges 14 afford convenient air-spaces 65 and prevent the charcoal or other combustible material from passing to and possibly escaping through the apertures 13. The flanges 14 also centralize the charcoal or other combustible material within the body 10 and aid 70 in enabling the combustible material to maintain a uniform temperature throughout said body 10.

The upper edges of the body 10 present uniform horizontal surfaces except at the opposite sides of said body, where standards 15 are formed, being cast integral with the body 10 to receive the pivoted eccentrics 16, having operating-handles 17, said eccentrics being disposed at the inner vertical sides of said 80 standards 15 in position to be utilized in locking the cover 11 upon the body 10. The standards 15 extend upward above the cover 11, and at what may be termed their "rear edges" said standards are formed at their 85 base with the vertical shoulders 18, against which the cover 11 abuts and which serve as convenient means for aiding in the application of the cover 11 to the body 10 and in securing said cover in rigid position. 90

The sad-iron while being of general elliptical outline in horizontal section is flattened at the central portion of its opposite sides, so that the standards 15 may stand parallel with each other and that the gates 34 may lie close 95 over the draft-apertures 13 and be capable of pivotal movement without in any material degree binding against the sides of the iron or drawing away from the surfaces thereof. The flattened portion of the opposite sides of 100 the iron extends from the bottom to the top of the body 10 and in width is substantially

equal to the length of the gates 34, the numerals 19 denoting in Fig. 1 those portions of the body 10 which are flattened.

The cover 11 is in one integral casting, and for convenience has cast with it the upwardly and outwardly extending end flues 20 20 and standards 21 21, the latter extending upward at the inner vertical portions of the flues 20 and receiving between their upper ends the customary handle 12, the latter being secured by screws 22 and being equipped with the usual sheet-metal guard 23. The flues 20 20 communicate directly with the interior of the body 10, as shown in Fig. 2, and the cover 11 is formed along the outer edges of its lower surfaces with the continuous downwardly-extending flange 24, adapted to fit within the upper edges of the body 10, as illustrated in Figs. 2 and 3. At the opposite sides of the iron the flange 24 is at the extreme outer edge of the cover 11, said cover 11 at its opposite side edges being flattened to pass between the standards 15, cast with the body 10, this flattened portion of the cover 11 being indicated in Fig. 1 by the numerals 25 25. Except at the flattened portions 25 of the cover 11 the edges of the latter extend outward beyond the continuous flange 24, so as to rest upon the upper edges of the body 10, as indicated by dotted lines in Fig. 1 and by full lines in Fig. 2. At the rear edges of the flattened portions 25 of the cover 11 are formed the shoulders 26, which when the cover 11 is in position engage the shoulders 18, formed at the lower rear portions of the standards 15, as shown in Fig. 1.

The cover 11 carries the flues 20, standards 21, handle 12, and guard 23, and when the cover 11 is in position upon the body 10 its flange 24 will be disposed within the upper edges of said body and the eccentrics 16 will be utilized for locking the cover 11 in position, said eccentrics 16 being at such time in the position in which they are illustrated in the drawings. When it is desired to remove the cover 11 from the body 10, the operator will by means of the levers or handles 17 turn the eccentrics 16 upward from the upper surface of the cover 11, thus freeing said cover, and then by an endwise movement imparted to the cover 11 the latter may be moved rearwardly from between the standards 15 and from below the eccentrics 16 and levers or handles 17. When it is desired to replace the cover 11 upon the body 10, the eccentrics 16 will be allowed to remain in their inoperative position, that being the opposite position to that in which they are shown in the drawings, and the cover 11 will be moved endwise in a direction toward the front end of the iron below the eccentrics 16 and between the standards 15 until the shoulders 26 of said cover engage the shoulders 18 formed on said standards 15, the contact of said shoulders with each other arresting the cover 11 at the proper position over the body

10, and thereupon after the cover 11 has been conveniently seated upon the body 10 the eccentrics 16 will be turned to the position illustrated in Fig. 2 and caused thereby to securely lock said cover in position.

When the iron is in use, the gates 34 may be opened or closed at will and either end of the iron may be pointed frontward, although it is preferable that, as illustrated, that half of the iron possessing the shoulders 18 26 be considered the rear end of the iron. Since the iron is pointed at both ends, it will not be necessary to so frequently change the position of the iron from end to end during the operation of ironing, since a rearward motion of the iron will not result in the unlocking of the cover 11 from the body 10.

I regard it as of importance that the draft-apertures 13 are at the opposite sides of the body 10, since in that position they materially aid in maintaining the iron at a uniform temperature with the maximum economy in the use of fuel. The draft-apertures 13, located at the opposite sides of the iron, operate with the flues 20 20, disposed at both ends of the iron, in effecting proper combustion within the body 10.

What I claim as my invention, and desire to secure by Letters Patent, is—

1. The sad-iron comprising the hollow body adapted to receive combustible material, the detachable cover, and the handle, said body being pointed at both ends and having the rigidly-fixed interior downwardly-extending elongated side flanges 14, the draft-apertures and gates at its opposite sides in line with the air-spaces formed between the inner sides of said body and said flanges, and the flues 20, 20, extending upward from both ends of said body and being at opposite ends of said handle; substantially as set forth.

2. The sad-iron comprising the hollow body adapted to receive combustible material, the detachable cover, and the handle, said body having integral therewith the rigid interior downwardly-extending elongated side flanges 14, the draft-apertures at its opposite sides in line with the air-spaces formed between the inner sides of said body and said flanges, the exterior gates 34 applied upon the opposite sides of the iron for controlling the said draft-apertures, and the upwardly-extending flues 20, 20, at the opposite ends of said body and communicating with the hollow interior thereof, the said cover closing the upper end of said body except at said flues 20; substantially as set forth.

3. The sad-iron comprising the hollow body adapted to receive combustible material, said body having at its opposite sides the vertical standards 15 at whose rear edges, at their base, are formed the shoulders 18, combined with the eccentrics 16 pivotally secured to the inner vertical sides of said standards and having operating-handles 17, and the removable cover, for said body, carrying the han-

dle and having at its opposite side edges shoulders 26, to contact with the said shoulders 18, said cover with the handle thereon being adapted to be moved to position lengthwise 5 of said body and below said eccentrics 16 until said shoulders 26 contact with and are arrested by said shoulders 18; whereupon said cover may be locked in position by means of said eccentrics; substantially as set forth.

10 4. The sad-iron comprising the hollow body adapted to receive combustible material and having integral therewith the rigid interior downwardly-extending elongated side flanges 14, the draft-apertures at its opposite sides in line with the air-spaces formed between the inner sides of said body and said flanges, the exterior gates upon the opposite sides of said body for controlling said draft-apertures, the vertical standards 15 extending upward from 15 the opposite sides of said body and having at their rear edges the shoulders 18, and the eccentrics 16 pivotally secured upon the inner vertical faces of said standards and having the operating-handles 17, combined with the 20 cover 11 adapted to fit upon the upper end of said body and having at its opposite ends the upwardly and outwardly extending flues 25 and standards 21, the handle 12 secured between said standards, and the shoulders 26 20 formed on the opposite side edges of said

cover for engagement with the said shoulders 18, the said standards being integral with the said flues 20 and the said cover being adapted to pass lengthwise of said body to its proper position below said eccentrics until arrested by the contact of said shoulders 26 with said shoulders 18, whereupon the said cover may be secured in position by means of said eccentrics; substantially as set forth. 35

5. The sad-iron comprising the body having 40 the standards 15, eccentrics 16, and side draft apertures and gates, said body being pointed at both ends and of flat formation at its opposite sides from its base to the top of said standards, whereby said standards become 45 parallel with each other and said gates may lie close to the sides of the iron, combined with the removable cover carrying the handle and adapted to fit upon said body between said standards and below said eccentrics, said 50 cover at its opposite edges adjacent to said standards being also of flat formation; substantially as set forth.

Signed at New York, in the county of New York and State of New York, this 3d day of 55 December, A. D. 1901.

GEORGE FINN.
